RAILWAY

Joseph B. Strauss, San Francisco, Calif.; Annette Strauss, John Sparks, and Henry C. Clausen, executors of said Joseph B. Strauss, deceased

Application March 29, 1937, Serial No. 133,600

5 Claims. (Cl. 238—4)

This invention relates to improvements in railways and more particularly to the structure and arrangement of tracks and runways on the road beds thereof.

- 5 Among the objects of the invention is to provide a roadway adaptable to the combined use of the conventional flanged railway rolling stock, and motortrucks and other automotive vehicles adapted to highway traffic on resilient tires.
- 10 Another object is to adapt the conventional railway to such combined traffic without disturbing the cross ties, ballast, and the road bed.

Another object is to reduce the overhead expense of railways by utilizing the right of way 15 between trains for motorcar traffic.

Other objects and advantages will appear as the description progresses.

"Door-to-door" delivery of merchandise by heavy hauling motortrucks has brought about 20 congestion of traffic upon highways originally intended for lighter automobile traffic. Costly rights of way for railways which are expensive to keep up are maintained for the occasional passenger or freight trains, between the headway of 25 which it is practicable to interpose motor traffic on fixed schedules in accordance with this invention.

In this specification and the accompanying drawing the invention is disclosed in its preferred form. But it is to be understood that it is not limited to this form, because it may be embodied in other forms within the purview of the claims following the description.

In the one sheet of drawings:

35 Fig. 1 is a vertical transverse section of a combined rail-runway constructed in accordance with this invention.

Fig. 2 is a similar view of a modification of the same.

40 Fig. 3 is a fragmentary detail in side elevation showing the incline derailing means.

In detail, the construction illustrated in the drawing, referring first to Fig. 1, comprises the conventional roadbed 1, having the cross ties 2 45 embedded therein and ballasted in the usual manner. The longitudinal stringers 3, 3 are laid on top of the cross ties 2 to which they are properly spiked. The conventional steel rails 4, 4 are set on top of these stringers and held 50 by the usual spikes 5, 5. It is the general practice in heavy load traffic to interpose plates between the base of the rails and the cross ties; this should be done as at 5', Fig. 3, between the rails and the stringers 3, 3 to prevent undue wear 55 on the stringers by the rails.

The parallel runways 6, 6—6, 6, are provided on opposite sides of the rails 4 for the tires 7, 7 of motor vehicles, as distinguished from rail traffic. These runways may be timbers similar to the stringers 3, or embossed metal floor plating 8, 5 arranged as shown in Fig. 2.

To brace the assembly shown in Fig. 1, it is advisable to provide the U shape braces 9, 9 at intervals. These braces are interposed between the base of the rails 4, extend over the runways 10 6, 6 and down to the tops of the cross ties 2, to which they are attached by the spikes 10, 10, which are toed inward to pull down on the braces to draw the stringers, runway timbers, and ties together. The lengths of the runways 6, 6 should 15 be such that the modulus of assembly will bring the ends of these timbers beneath the width of the braces 9, to prevent the ends of the timbers splintering or otherwise interfering with the rubber tires 7. These braces should be repeated at 20 intervals throughout the length of the runways to prevent warping and twisting of the timbers with respect to each other and the cross ties 2.

The dual tire arrangement shown in Fig. 1 is common practice in heavy duty motortrucks. 25 The flange disc 11 can be interposed between each dual set of tires; these discs are adapted to bear against the inner edges of the heads of the rails 4, 4 to guide the tires 7, 7 and maintain them in proper alinement with the runways 6, 6 as required. As a further precaution the spreaders 12, 12 can be large enough in diameter so that their peripheries can rest upon the tops of the rails 4, should one or more of the tires 7 collapse. This will in an emergency permit the truck to 30 proceed to a point where the vehicle can pull off of the right of way.

At switch points the runways 6, 6 can be inclined as at 6', see Fig. 3, similarly to "derailing" switches, to lift the motortruck tires 7, 7 to near 40 the level of the tops of the rails, which will clear the flange discs 11, 11 from the rails and permit the motor vehicle to proceed under control of its own steering gear. Other forms of guiding the tires by means of the rails may be provided upon 45 the motortrucks, which may be attached and detached from the trucks as desired.

Having thus described this invention, what is claimed and desired to secure by Letters Patent is:

1. A railway having a pair of interspaced rails; runways adjacent and below the level of the tops of said rails; in combination with a vehicle having wheels supported upon resilient tires adapted to run upon said runways; and guiding flanges 55

on said wheels coaxial with and above the supporting treads of said tires and guided by said rails.

2. A railway having a pair of interspaced rails; runways on the opposite sides and below the level of the tops of said rails respectively; in combination with a vehicle having wheels with twin resilient supporting tires adapted to run on said runways on opposite sides of said rails respectively; and a coaxial flange on said wheels between each of said twin tires of less diameter than said tires and guided by said rails.

3. A railway having cross ties ballasted in a roadbed; steel rails spaced apart on said ties and adapted to carry the load of steel tired vehicles operating thereon; separate runways on said ties adjacent to said steel rails and below the level of the tops thereof and adapted to carry the load of vehicles having pneumatic tired wheels operating thereon; guide means on said wheels above the treads of said pneumatic tires coaxing with said steel rails and adapted to guide said pneumatic tired wheels.

4. A railway having a pair of interspaced rails; runways on opposite sides and below the tops of each of said rails respectively; in combination with a vehicle having dual wheels arranged on opposite sides of said rails and resting upon said runways respectively; and guiding flanges between each of said dual wheels and engaging the sides of their respective rails above said runways.

5. A railway having cross ties ballasted in a roadbed; interspaced traction plate runways supported upon said cross ties; rails arranged intermediate the width of and extending above said runways; in combination with a vehicle having dual wheels adapted to run on said runways on opposite sides of said rails respectively; and guide flanges between said wheels adapted to engage the sides of their respective rails above the treads of said wheels.
